WRITING INSTRUMENT

Charles K. Lovejoy, Atlanta, Ga., assignor to Scripto,
Inc., a corporation of Georgia

Filed Oct. 18, 1961, Ser. No. 67,137

Term of patent 14 years
(Cl. D74—17)

Fig. 1

Fig. 2

Fig. 3

FIG. 1 is a front elevational view of a writing instrument embodying my new design;

FIG. 2 is a top plan view; and

FIG. 3 is a bottom plan view thereof.

The dominant features of my design reside in the combination, on the writing instrument disclosed, of the metallic upper barrel portion having transverse engine chasing thereon and the forward plastic barrel portion having harmonizing transverse scoring at its forward end together with the specific concave-shaped tip configuration all as shown in solid lines on the drawing.

I claim:

The ornamental design for a writing instrument, as shown and described.
